UNITED STATES PATENT OFFICE.

CHARLES A. REMELIUS, OF NEW YORK, N. Y., ASSIGNOR TO EDWARD H. FALLOWS, TRUSTEE, OF NEW YORK, N. Y.

SEPARABLE BRAKE SHOE AND HEAD.

No. 854,761.

Specification of Letters Patent.

Patented May 28, 1907.

Application filed March 30, 1906. Serial No. 308,834.

To all whom it may concern:

Be it known that I, CHARLES A. REMELIUS, a citizen of the United States, and a resident of New York, borough of Manhattan, in the county of New York and State of New York, have made and invented certain new and useful Improvements in Separable Brake Shoes and Heads, of which the following is a specification.

10 My invention relates to an improved separable brake shoe and head, and more particularly that kind or style adapted for use upon the wheels of railway cars. As now generally constructed the head and shoe are combined or cast in one piece, the consequence being that when the shoe has been worn down by friction and incapable of further use, not only has the shoe to be discarded, but also the head, cast integral therewith,

15 resulting in a material loss, especially where large numbers of these devices are in use.

The use of a combined head and shoe has heretofore been rendered necessary by reason of the fact that there is but little room or space between the several parts to which the brake shoe and head are attached, (as for instance, the truck bolster, brake beam, etc.,) whereby to detach the shoe from the head as ordinarily constructed, in order to substitute

20 a new shoe.

The object of my invention is to construct a separable head and shoe, the parts being so formed that even though the space be limited, the shoe may be easily and readily detached from the head, and this without in any way detaching the head from the brake beam.

A further object of my invention is to provide a shoe containing the usual amount of wearing metal, and so constructed that when worn down to such an extent as to be unfit for further use, it may be detached from the head and another substituted therefor, thereby utilizing the old head, which has heretofore been discarded with the worn out shoe.

With these and other ends in view, the invention consists in certain novel features of construction and combinations of parts, as will be hereinafter fully described and specifically pointed out in the claims.

In the accompanying drawings, Figure 1 is

a top plan view of a brake head and shoe constructed in accordance with my invention. Fig. 2 is a view in side elevation thereof. Fig. 3 is a sectional view taken on the line 3—3 of Fig. 1. Fig. 4 is a top plan view of the shoe, the head being detached therefrom. Fig. 5 is a sectional view taken on the line 5—5 of Fig. 4. Fig. 6 is a sectional view taken on the line 6—6 of Fig. 4. Fig. 7 is a perspective view of one of the wires bent to form part of the attaching lug. Fig. 8 is a top plan view showing a modified form of attaching lug. Fig. 9 is a sectional view taken on the line 9—9 of Fig. 8. Fig. 10 is a detached view of a modified form of lug, illustrated in Figs. 8 and 9. Fig. 11 is a bottom plan view of the head. Fig. 12 is a view in side elevation thereof. Fig. 13 is a top plan view thereof.

Referring to the drawings, A represents the body of the shoe adapted to bear upon the tread of the wheel, and B the flange, adapted to contact with the flange of the wheel, said shoe being made of cast iron or of a combination of relatively hard and soft metals, whereby to increase the frictional and wearing qualities.

In order to render the shoe as compact as possible, I form the attaching lug of wrought, ductile or other metal, tougher in character than the cast iron of which the body of the shoe is preferably formed, as for instance, of bent wires or rods C, one of which is illustrated in Fig. 7, these rods or wires being bent at about the middle of their length and extended upwardly into the loop c, the extreme ends c¹ of each of the rods or wires, being bent downwardly to anchor or embed the same in the body of the shoe. Two of these bent rods or wires are preferably used or employed, as clearly illustrated in Figs. 4 and 5, the loops c being located at about the center of the length of the shoe forming the key-lug 95 for attaching the brake head thereto.

Instead of employing a bent rod or rods or wires, to form the attaching lug, I may, if desired, use what I term the strap lug D, as illustrated in Figs. 8, 9 and 10, this lug being also formed of wrought, ductile, or other comparatively tough metal, the ends d of the lug being bent outwardly for locking or anchoring the same under the wires d¹ embedded in the

metal forming the body A of the shoe, and extending lengthwise thereof. This attaching lug or loop sits comparatively close to the back of the shoe A, the top of the same lying in substantially the same plane as the top of the flange B, in order that the shoe be as compact as possible and properly fit the brake head hereinafter described. To this shoe is attached the brake head comprising a plate E having formed on the under side thereof the lugs e straddling the key-lug of the shoe, these lugs e being comparatively short, in order to allow the head to fit down closely upon the shoe, and provided with a key opening e^1 therein for the passage of the attaching key F. The plate E has extending from the lower end thereof the arms G, G¹, the under-side of the ends of which rest upon the back of the shoe, the extreme ends g abutting against the end stop g^1 also formed on the back of the shoe and straddling the comparatively high guide lug g^2 thereon, the side of the inner of said arms G¹ resting against the wall H of the flange B of the shoe, this side or wall H being made straight in order to form a solid bearing or abutment for the straight impinging side of said arm G¹.

The plate E is of sufficient width to extend over the body A and flange B of the shoe, in order to provide a wide bearing therefor and prevent the same from rocking on the shoe when in use, the elongated bearing surface being shown at I, Fig. 11. From the upper side of the plate E also extend the arms K, K¹, the inner one of which, K¹, also bears against the straight wall H of the flange B, to assist in holding the head rigidly on the shoe, the extreme ends k abutting against the end stop g^3 and straddling the lug g^4 formed on the back of the shoe. This plate E is also provided with the attaching plate L, whereby the head may be bolted or otherwise secured to the brake beam (not shown), said plate L being of corresponding shape to said beam, that in the present instance comprising the plates l¹, l² and base plate l³, to accommodate a beam rectangular in shape and extending across the entire width of said plate E to afford a wide bearing therefor.

From the foregoing it will be understood that a separable head and shoe thus constructed, that is, a shoe having a comparatively low and tough key-lug with high guide lugs, and the flange formed with a straight wall, and the head provided with a wide bearing plate extending over the body and flange of the shoe with arms extending from both the upper and lower sides of said plate, the inner arms bearing against the flat or straight wall of the flange of the shoe, and having comparatively short key-lugs to fit over the key-lug of the shoe, is very compact, strong and durable, and that

the shoe, containing the ordinary amount of wearing metal, may be easily and readily attached to and detached from the head without detaching the latter from the brake beam, even though the space between the parts of the braking apparatus be very limited.

It will of course be understood, that the invention is not to be limited to the use of a plate L for attachment to the brake beam, as it is evident that such may be altered in shape or size to accommodate a lever or any other part of the braking apparatus, the head being provided with a sleeve or cylindrical bearing M for the accommodation of a link or hanger, whereby to suspend the device, this sleeve or bearing extending entirely across the shoe and overlying both the body and flange thereof.

It will be further seen that the head is comparatively short, while the shoe is of the usual length, and that the arms G, G¹ and K, K¹ do not extend over the flange of the shoe, as is usually the case, the consequence being that should the ends of the shoe be first worn away, the head, nor any part thereof, will not be destroyed by coming in frictional contact with the wheel.

Having fully described my invention, what I claim as new and desire to secure by Letters Patent, is:

1. The combination with a brake shoe comprising a body and flange, and provided with a key-lug of a brake head having a bearing surface of sufficient width to extend over said body and flange, substantially as described.

2. The combination with a brake shoe comprising a body and flange provided with a key-lug, of a brake head comprising a plate of sufficient width to extend over said body and flange of the shoe, and arms extending from said plate adapted to rest upon the body of said shoe, substantially as described.

3. The combination with a brake shoe comprising a body and a flange, and provided with a key-lug, the wall of said flange adjacent to the body of the shoe being straight, of a brake head provided with arms adapted to bear against said wall, substantially as described.

4. The combination with a brake shoe comprising a body and flange and provided with a comparatively low key-lug, of a brake head comprising a plate of sufficient width to extend over said body and flange of the shoe and having arms extending from the upper and lower ends of said plate, adapted to rest on the body of said shoe and against the wall of said flange, substantially as described.

5. The combination with a brake shoe comprising a body and flange, said body being provided with a comparatively low key-lug and high guide lugs, of a brake head com-

prising a plate extending across said shoe and provided with arms extending from the upper and lower ends of said plate and straddling said guide lugs, the inner of said arms adapted to bear against the wall of the shoe flange, substantially as described.

Signed at New York, borough of Manhat-

tan, in the county of New York, and State of New York, this 28th day of March, A. D. 1906.

CHARLES A. REMELIUS.
